TRACK SANDING EQUIPMENT

Guilford S. Turner, Berwyn, Ill., assignor to
 Morris B. Brewster Co. Inc., Chicago, Ill., a cor-
 poration of Illinois

Application May 4, 1940, Serial No. 333,295

3 Claims. (Cl. 291—16)

The invention relates to track-sanders for locomotives.

It has been common practice to provide sand-traps provided with nozzles for delivering air under pressure to discharge sand from the trap and through the pipes for delivering the sand to the rails and also to provide means for delivering momentary clean-out blasts directly into the delivery pipes at the beginning and end of each sanding operation and to control the air for the nozzle and for the clean-out blast from a single manually shiftable valve-operating lever.

In the equipment heretofore used it sometimes occurred that the engineer, in emergencies, would not complete the stroke of the valve-lever from its normal position into position to set the valve for delivering sand to the nozzle so that a blast would be delivered to the clean-out duct but not to the nozzle for delivering sand to the rails. This resulted in a failure to sand the rails.

One object of the present invention is to provide improved lever-operated mechanism for conjointly controlling the clean-out blasts and the sand-delivery blasts which automatically prevents the valve from being set into position to continue the clean-out blasts through error in the movement of the valve-lever by the engineer.

Another object of the invention is to provide improved mechanism for manually controlling the clean-out blasts and the sand-delivery blasts for the sander.

Other objects of the invention will appear from the detailed description.

The invention consists in the several novel features which are hereinafter set forth and are more particularly defined by claims at the conclusion hereof.

In the drawing: Fig. 1 is a side elevation of sanding equipment embodying the invention. Fig. 2 is a side elevation of the control-valve, the handle being shown in section. Fig. 3 is a section taken on line 3—3 of Fig. 2. Fig. 4 is a section taken on line 4—4 of Fig. 3. Fig. 5 is a view illustrating the valve-disk in its normal or closed position in the valve-casing.

The sanding equipment comprises at least one sand-trap 8 which is provided with an inlet for receiving sand from a pipe 9 to which the sand flows from a sand-box in the dome of the locomotive, as well understood in the art. The trap is provided with an outlet 10 to which is connected a pipe 11 for conducting sand to a track-rail. A nozzle 12 in the sand-trap is adapted to deliver air under pressure into the trap-conduit to discharge the sand through duct 10 into pipe

11. An air-pipe 13 is connected to the casing of the trap to deliver air through a chamber 13' to the nozzle. A duct 14 is provided in the casing of the trap to direct a clean-out blast into the pipe 11 and a pipe 15 is connected to deliver air to said duct.

In the operation of this equipment, air for a momentary blast is supplied through pipe 15 to clean out the pipe 11 before air for discharging sand is delivered to nozzle 12 and also at the end of each sanding operation.

The valve-mechanism for controlling the supply of air for the nozzle 12 and the clean-out blast comprises a valve-casing composed of a body-section 18 and a cover-section 19 removably secured together by bolts 20; a valve-disk 16 rotatably mounted in the casing; and a hand-lever 17 for shifting the valve-disk. Hand-lever 17 is fixedly secured to a stem 21 which extends through, and is rotatable in, the body-section 18 and is provided with a spline 22 at its inner end which fits in a socket in one face of the disk 16 for rotating the disk with the hand-lever 17. The valve mechanism illustrated is adapted to control the delivery of sand to the nozzles and clean-out ducts of a pair of traps for sanding different pairs of driving-wheels or driving-wheels on the opposite sides of the locomotives, only one sand-trap and the connections for one trap being illustrated. The cover-section 19 is provided with a chamber 23 to which air is constantly supplied from the usual supply reservoir by a pipe 24 which is connected to the bottom of cover-section 19. Valve-disk 16 is provided with a series of ports for controlling the flow of air through the body-section 18 to the sanding-nozzles and the clean-out ducts of a pair of traps. A chamber 26 is formed in body-section 18 and is connected by a pipe 27 to pipe 15, which delivers air to the nozzle 12 of one of the sand-traps for sanding a rail in front of one of the driving-wheels. A chamber 28 is formed in the opposite side of body-section 18 and is connected by a pipe 29 to the nozzle of another trap (not shown); and a chamber 30 which is connected by pipes 31, 32 to pipes 15 which deliver air to the clean-out ducts 14 of the sand-traps, respectively. Partitions 33 and 34, integral with body-section 18, separate chambers 26, 28 and 30 from one another. A duct 35 extends from seat 36 which is engaged by the inner face of disk-valve 16 to chamber 26, for the flow of air through pipe 27 to the nozzle 12 of one trap. A duct 37 connects valve-seat 36 to chamber 28 for the flow of air to pipe 29 and the nozzle 12 of the other trap. A pair of ducts 38,

39 connect seat 36 to chamber 30 for the flow of air to pipes 31, 32 and the clean-out ducts.

Valve-disk 16 is provided with a pair of through-ports 40, 41, which normally close ducts 35, 37 and which are adapted to simultaneously register with said ports respectively when the valve is shifted into sanding position. Valve-disk 16 is also provided with a pair of ports 42, 43 which normally close ducts 38, 39 and simultaneously register with said ports, respectively, during the movement of the disk between its sanding and closed positions. The plurality of ports between chamber 30 and valve-seat 36 provides for a momentary blast of great volume to the clean-out ducts 14 in the traps.

The throw of hand-lever 17 is limited to move the valve-disk 16 between its predetermined closed position and its sanding position, by abutments 44 and 45 integrally formed on the body-section 18 of the valve-casing. The lever is yieldingly locked in its normal and sanding positions by a device which comprises a plunger 46 which is slidably mounted in a socket 47 in the handle 11 and carries a roller 48 at its inner end. Said roller is adapted to ride on a track 18^b which is integrally formed on the body-section 18. A spring 49 in socket 47 presses the plunger 46 toward the axis of the lever. A pin 50 extending through an elongated notch 51 in one side of plunger 46 holds the plunger against rotation in socket 47. This track on which the roller 48 rides comprises a curved recess 52 positioned to yieldingly lock the lever 17 in its normal position with the valve-disk 16 closed, and a notch 53 positioned to yieldingly lock the lever in sanding position at the end of a full stroke of the lever 17. Between notches 52, 53 the track 18^b is provided with a V-shaped portion or cam having inclined sides 54 and 55 on which the roller 48 rides and which causes the lever to be automatically swung to either side of the apex. The apex of the V-shaped track is positioned at the point where the roller 48 will engage it at the time that the ports 42, 43 for delivering the clean-out blasts are open to deliver air into chamber 30. When the engineer shifts lever 17 from its normal position for a sanding operation, roller 48 will ride out of notch 52 and outwardly on the inclined side 54 of the track and this movement of the roller will force plunger 46 outwardly and compress and store power into spring 49 until the roller reaches the apex of the camportion of the track. After the roller passes over the apex, it will be forced downwardly by spring 49 into engagement with the inclined side 55 of the track until it passes into notch 53 where the lever will be yieldingly locked and the valve-disk 16 will be in sanding position with the ports 40 and 41 in the valve-disks open to deliver air to chambers 26, 28, respectively, and to the nozzles 12 in the sand-traps. In the movement of the lever 17 between its normal and sanding positions, ports 42, 43 will be simultaneously and momentarily opened to deliver air into the chamber 30 for the clean-out blasts to ducts 14 in the sand-traps. The point of the V-shaped cam prevents the roller remaining in position to keep the air supplied to the clean-out ducts. When the lever 17 is shifted until the roller reaches the apex of the track between inclined sides 54, 55, the force of spring 49 will be applied to plunger 46 and roller 48 to rotate valve-disk so that the ports 42, 43 will not remain open. The track forces roller 52 under the spring pressure

applied to it to automatically restore the lever to its normal position or to complete the stroke of the lever to its sanding position. The roller 48 is operable inwardly or outwardly only by the track and it is impossible through careless operation, or an incomplete stroke of lever 17, to keep the valve-disk in position for continued operation of the clean-out blasts when sanding of the rails by air from nozzles is intended. If the engineer releases the lever 17 at any intermediate point between its normal and sanding positions, spring 49, the track 18^b, and roller 52 will shift the lever 17 to either complete the stroke of the lever to sanding position or to return the lever to its normal position. When the lever is returned to its normal position no air will flow either to the nozzles or to the clean-out ducts and this condition will be readily observed by the engineer so that another stroke can be imparted to the lever to its sanding position by the engineer. If the handle is released, after the roller 48 has passed the apex of the track, the spring 49 will cause the lever, through the action of roller 48 on the track, to be shifted to its sanding position and cut off the clean-out blasts. As a result, there is practically no likelihood of keeping the clean-out blast open when it is intended to sand the tracks.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In controlling mechanism for a sand-trap provided with an air nozzle for discharging sand from the trap for application to a rail and a duct for a momentary clean-out blast of sand, the combination of a valve-casing, means for supplying air under pressure to the casing, a movable valve-element in the casing, the casing and said element being provided with means for successively controlling the supply of air to the nozzle and to the clean-out duct, said element being movable from a normal position to cut off the supply of air to the nozzle and said duct to a sanding position for delivering air only to the nozzle and being adapted, in an intermediate position, to open the supply of air to the clean-out duct, a lever for manually shifting said element, and means for automatically shifting the lever and said element out of the intermediate position either to the closed position or the sanding position for preventing the element from continuing the supply of air to the clean-out duct when the lever is released, said means being adapted to hold the lever in sanding position.

2. In controlling mechanism for a sand-trap provided with an air nozzle for discharging sand from the trap for application to a rail and a duct for a momentary clean-out blast for sand, the combination of a valve-casing, means for supplying air under pressure to the casing, a valve-element rotatably mounted in the casing, the casing and said element being provided with means for successively controlling the supply of air to the nozzle and to the clean-out duct, said element being rotatable from a normal position to cut off the supply of air to the nozzle and said duct to a sanding position for delivering air only to the nozzle and being adapted, in an intermediate position, to open the supply of air to the clean-out duct, a manually shiftable lever

fixed to, and for rotating, said element, and means for automatically rotating the lever and said element out of the intermediate position either to the closed position or to the sanding position for preventing the element from continuing the supply of air to the clean-out duct when the lever is released, said means being adapted to hold the lever in sanding position.

3. In controlling mechanism for a sand-trap provided with an air nozzle for discharging sand from the trap for application to a rail and a duct for a momentary clean-out blast for sand, the combination of a valve-casing, means for supplying air under pressure to the casing, a valve-element rotatably mounted in the casing, the casing and said element being provided with means for successively controlling the supply of air to the nozzle and to the clean-out duct, said

element being rotatable from a normal position to cut off the supply of air to the nozzle and said duct to a sanding position for delivering air only to the nozzle and being adapted in an intermediate position to open the supply of air to the clean-out duct, a manually operable lever fixed to, and for rotating, said element, and means for automatically shifting the lever and said element out of the intermediate position or to the sanding position for preventing the element from continuing the supply of air to the clean-out duct when the lever is released, said means being adapted to hold the lever in sanding position, said automatic means comprising a spring mounted in said lever, a cam-track and a roller held by the spring to engage the track.
